UNITED STATES PATENT OFFICE.

AUGUSTUS II. HEISEY, OF IDLEWOOD, PENNSYLVANIA.

DESIGN FOR A GLASS VESSEL.

SPECIFICATION forming part of Design No. 28,180, dated January 18, 1898.

Application filed November 12, 1897. Serial No. 658,345. Term of patent 3½ years.

To all whom it may concern:

Be it known that I, AUGUSTUS II. HEISEY, a resident of Idlewood, in the county of Allegheny and State of Pennsylvania, have invented a new and original Design for Glass Vessels; and I do hereby declare the following to be a full, clear, and exact description thereof.

My invention relates to designs for vessels formed of glass.

In the accompanying drawing I have illustrated by perspective view a glass vessel embodying my invention.

The letter *a* designates the base of a glass vessel, and above said base is the notched ring *a'*. Above the notched ring *a'* is the bulbous portion *b*, projecting out beyond the base. At the upper end of the bulbous portion *b* is the notched ring *c'*. Extending up

from the notched ring *c'* is the inwardly-curved portion *c*, which forms the neck of the vessel, said inwardly-curved portion extending out to form the outwardly-flaring mouth *d*. On the upper edge of this vessel are the beads *e*, which extend around a portion of the open end of the vessel.

The letter *f* represents the handle of the vessel.

What I claim is—

The design for a glass vessel as herein shown and described.

In testimony whereof I, the said AUGUSTUS II. HEISEY, have hereunto set my hand.

AUGUSTUS II. HEISEY.
